UNITED STATES PATENT OFFICE

2,372,680

TOY

Adolph Pitar, Brooklyn, N. Y.

Application February 29, 1944, Serial No. 524,368

4 Claims. (Cl. 46—61)

This invention relates to toys and the same has particular reference to a toy consisting of a rollable member having a string secured thereto adjacent the opposite ends thereof for suspending the member horizontally between the leads of the string so that upon imparting vertical reciprocatory movement to the string the leads thereof will alternately wind and unwind about the said rollable member to thereby cause the same to roll up and down the leads of the string.

The invention further comprehends a toy of said character in which the rollable member includes oppositely disposed conical portions to which the ends of the string are secured so as to effect a rapid rolling of said member up and down the leads of the string as the same is wound and unwound about the conical portions upon imparting vertical reciprocatory movement to the string.

The invention also provides a toy adapted to be pulled by the string for rolling the rollable member upon a supporting surface to thereby initially wind the leads of the string about the conical portions thereof so as to facilitate the rolling movement of the rollable member up and down the leads of the string upon imparting vertical reciprocatory movement to the string and for such purpose the rollable member includes a centrally disposed annular portion adapted for rolling engagement with the supporting surface and conical end portions extending outwardly from the annular portion with the apices of the conical portions disposed outermost about which the leads of the string are wound in helical formation.

With the foregoing and other objects in view, reference is now made to the following specification and accompanying drawing in which are illustrated the preferred embodiments of the invention.

In the drawing:

Fig. 1 is a perspective view of a toy constructed in accordance with the invention.

Fig. 2 is a similar view thereof illustrating the manner of using the same and with the leads of the string wound about the ends of the toy.

Fig. 3 is an enlarged view showing the rollable member partly in section and with the leads of the string broken away.

Fig. 4 is a similar view of a modified form of the invention.

Referring to the drawing by characters of reference, the toy includes an elongated rollable member 10 consisting of a medially disposed

annular portion 11 and oppositely disposed outwardly tapered or conical end portions 12 and a flexible member such as a string 13 secured at its ends to the tapered or conical end portions at points spaced inwardly from the remote outer ends thereof. In the form of the invention illustrated in Figures 1 to 3 inclusive of the drawing, the annular portion 11 is made of a material such as wood so as to give weight to the medial portion of the rollable member, while the conical end portions 12 are preferably hollow and telescopically secured by any desired means upon the tapered ends of the annular portions 11.

In using the toy the string 13 is held in looped or inverted V formation with the rollable member suspended horizontally between the ends of the string and by imparting vertical reciprocatory movement to the string as indicated by the arrows in Figure 2 of the drawing the ends of the string will alternately wind and unwind about the conical end portions in helical formation so as to cause the rollable member to rapidly roll up and down the leads of the string. The toy is also adapted to be pulled by the string for rolling the rollable member 10 upon a supporting surface so as to initially wind the leads of the string about the conical end portions 12 to thereby facilitate the rolling movement of the said member up and down the leads of the string when the rollable member is suspended between the leads thereof and vertical reciprocatory movement is imparted thereto.

In the form of the invention illustrated in Figure 4 of the drawing, the rollable member 14 consists of oppositely disposed taper or conical end portions 15 which are preferably hollow so as to be of light weight and therefore readily revolvable and which may be constructed of any desired material such as compressed fiber, tin or other equivalent materials. As illustrated the conical end portions are disposed with their bases in abutting relation and a decorative covering 16 is adhesively or otherwise secured to the outer faces thereof for coupling the same together in abutting relation. The string 17 may be secured to the end portions 15 inwardly of the extreme ends thereof in any desired manner such as by training the ends of the string through openings 18 and knotting the end portions 19 which protrude through the openings in the apices thereof. Sound producing elements 20 may be located within the conical end portions so as to create a rattling sound when the rollable member is revolved.

I claim:

1. In a toy of the indicated character, an elongated rollable member having oppositely disposed conical portions and a string attached at its ends to the conical portions adjacent the ends thereof and adapted to be formed into a loop with the rollable member suspended between the ends of the string so as to effect a winding and an unwinding of the ends of the string about the conical portions upon imparting a vertical reciprocatory movement to the string to thereby produce a rolling of the rollable member up and down the string.

2. In a toy, an elongated rollable member having oppositely disposed conical portions arranged with their smaller ends outermost and a string attached at its ends to the conical portions adjacent the smaller ends thereof and adapted to be formed into a loop with the rollable member suspended between the ends of the string so as to effect a winding and an unwinding of the ends of the string about the conical portions upon imparting a vertical reciprocatory movement to the string to thereby produce a rolling of the rollable member up and down the string.

3. In a toy, an elongated rollable member in-

cluding a centrally disposed annular section and oppositely arranged hollow conical sections fitted upon the opposite ends of the annular section with the smaller ends of the conical sections disposed outermost and a string attached at its ends to the conical sections adjacent the smaller ends thereof and adapted to be formed into a loop with the rollable member suspended between the ends of the string so as to effect a winding and an unwinding of the ends of the string in spiral formation about the conical sections upon imparting a vertical reciprocatory movement to the string to thereby produce a rolling of the rollable member up and down the string.

4. In a toy, an elongated rollable member having oppositely disposed tapered portions and a string attached at its ends to the tapered portions and adapted to be formed into a loop with the rollable member suspended between the ends of the string so as to effect a winding and an unwinding of the ends of the string about the tapered portions upon imparting a vertical reciprocatory movement to the string to thereby produce a rolling of the rollable member up and down the string.

ADOLPH PITAR.
